[57] CLAIM

The ornamental design for a clarinet ligature, as shown and described.

DESCRIPTION

FIG. 1 is a front elevational view of a clarinet ligature showing my new design, the rear elevational view being a mirror image thereof;

FIG. 2 is a right end elevational view of the clarinet ligature of FIG. 1;

FIG. 3 is a left end elevation of the clarinet ligature of FIG. 1;

FIG. 4 is a top plan view of the clarinet ligature of FIG. 1;

FIG. 5 is a bottom plan view of the clarinet ligature of FIG. 1; and,

FIG. 6 is a sectional view thereof, taken on line 6—6 of FIG. 1.
